COLLAPSIBLE RAZOR

Walter C. Koval, Los Angeles, Calif., assignor of one-third to Daron Borian and one-third to Lawrence A. Sackman, both of Hollywood, Calif.

Application July 24, 1953, Serial No. 369,990

4 Claims. (Cl. 30—47)

This invention relates to a collapsible razor and more particularly to a collapsible razor wherein the razor when not in operating position is housed in a cover, approximately the same size as a paper match box cover, but is adapted to be expanded to the normal razor size. In addition, the razor is constructed of such a material and in such a manner that it may readily be disposed of without any measurable financial loss.

There often arises instances wherein men find themselves in a situation where it is imperative that they have an immediate shave, but find to their dismay that there is no barber shop open or available or that they have no razor with which to shave themselves. With the standard razors presently available on the market, it is not practical to purchase a new one in such a situation and since you cannot always foresee when this calamity will occur, it is even less practical to carry a home razor with you.

To alleviate this situation, applicant has invented a new and useful collapsible razor that fits into a housing, the size of an ordinary paper box match cover and which may be assembled into a standard razor and furthermore, applicant's razor is constructed of such material that it does not prohibit the ready disposal of the same.

It is therefore a primary object of this invention to provide an inexpensive and economical collapsible razor.

It is a further object of this invention to provide a collapsible razor that may be housed in a small compact housing when not in use, but which may be expanded when in use so as to conform with a standard razor's size, shape and form.

It is an additional object of this invention to provide an inexpensive and economical collapsible razor so that it may be disposed of after being used one or more times without being prohibitive in cost. A still further object of this invention is to provide a means of constructing a collapsible razor out of paper or cardboard so that it may readily be disposed of after a single use.

An additional object of this invention is to provide a collapsible razor that may be simply and readily expanded into a normal razor's size, shape and form.

Other and more specific objects and advantages will become apparent from the following detailed description, when read in conjunction with the accompanying drawings which illustrate a collapsible razor in accordance with one embodiment of this invention. It should be understood, however, that this invention is not limited to any particular form, but that various changes may be made in details, but within the scope of the appended claims without departing from the spirit of this invention.

In the drawings:

Figure 1a is a front elevational view of the collapsible razor shown with the cover in a closed position.

Figure 1b is a rear elevational view of the collapsible razor shown with the cover in a closed position.

Figure 1c is a top view of a collapsible razor taken along arrows 1c of Figures 1a and 1b.

Figure 1d is a bottom view of the collapsible razor taken along arrows 1d of Figures 1a and 1b.

Figure 2 is an inside front elevational view of the collapsible razor with the cover open.

Figure 3 is a side elevational view of the collapsible razor shown in Figure 2.

Figure 4 is a front elevational view of the collapsible razor showing the positioning of one of the side flaps in the assembling of said razor.

2

Figure 5 is a side elevational view of the collapsible razor shown fully assembled.

Figure 6 is a rear elevational view of the collapsible razor shown fully assembled.

Figure 7 is another embodiment of the razor head employed in the construction of the collapsible razor.

Referring to the drawings, there is shown in Figures 1a through 1d, the collapsible razor 11 disassembled and completely incased in the housing 12. In this position the razor is approximately two (2) inches by one and one-half (1½) inches and has the general appearance of a standard closed paper match cover. The cover for the housing 12 may be constructed of a single sheet of water-repellent paper, cardboard or other suitable material and for purposes of illustration only, applicant will describe one embodiment constructed out of a single sheet of water-repellent paper 14 of approximately four and one-half (4½) inches in length and one and one-half (1½) inches in width. It should be noted that the dimensions are only given for purposes of describing a preferred embodiment of applicant's invention, but in no way is meant to limit applicant's invention.

The inside cover 15 of housing 12 is scored in various areas to facilitate the assembling of the razor as will be hereinafter more fully described. Running the length of the inside cover 15 are two slightly diverging scored lines 16 as shown in Figures 2 and 4. Transversing the inside cover 15 are two parallel scored lines 17. The purpose of which will be described in detail infra. Referring to Figure 1b there is shown a third transverse scored line 18 which joins with two thirty degree (30°) diagonal cuts 19 in the cover 15. One edge 21 of the housing 12 is bent to form a flap 22 which is used to house the razor head 31, both of which will be more fully described below.

The razor head 31 is constructed of a razor guard 32, constructed of any suitable material such as plastic and a razor blade 33. Both the razor blade 33 and guard 32 are mounted in a base 34 which in turn is incased and housed in an area formed by bending flap 22, as shown in Figure 3. The entire razor head is then secured in position by any suitable means such as a staple 36, shown in Figures 1a and 1b and Figures 2 and 4.

In Figure 7 there is shown another embodiment of razor head 31 which shows the razor guard 32 and base 34 constructed of a single piece of material such as plastic with the razor blade 33 mounted therein. This is merely a variation that may be employed in the construction of the razor head.

Mounted on the inside cover 15 of housing 12 is shaving soap 41 secured thereto by any suitable gluing agent. It should be noted that the shaving soap is so shaped and positioned so as to fit within the area defined by scoring lines 16 and 17. If desired, an aseptic pencil may be mounted in the upper area defined by scored line 16 and 17, although the same is not shown in the drawings. The scoring on the inside cover 15 serves the following purposes: The transverse scoring 17 permit the cover for the housing 12 to form the top of the housing 34 as shown in Figure 1c. The diagonally diverging scoring 16 permits flaps 44 to be bent to their desired position as shown in Figure 4 and which will be more fully described hereinafter. The third transverse scoring 18 together with the 33 degree angle cuts 19 permit the razor head 31 to be positioned at the required thirty degree (30°) angle as shown in Figure 5 and which will be more fully described below.

On the rear cover there are two vertical cuts 46, the area surrounded by the cuts 46 is reinforced by a suitable metallic strip such as a thin gage aluminum strip 47, one end of which is secured to the inside cover 15 of the housing 12 at point 48; the other end of strip 47 is mounted under the staple 36 as shown in Figures 2, 4, 5 and 6. The purpose of the cuts 46 and aluminum strip 47 is to brace the razor head 31 when in operating position and to further act as a stop when in said position as shown in Figures 5 and 6. When in said position, the end of the aluminum strip 47 mounted under the staple 36 is extended beyond said staple and bent as is at 49 so as to act as a lock as shown in Figure 5.

The procedure in assembling and operating the col-

lapsible disposable razor is as follows: As shown in Figures 1a through 1d, the razor is disassembled and housed in cover 12, when in such a position the razor gives the appearance of a paper match book cover as it is approximately the same size. In such a position the razor is easily and safely portable without any danger of receiving any cuts from an exposed razor blade since the same is completely incased in housing 12. To assemble the razor, one end of cover 15 is extended, as shown in Figure 2, flaps 44 are then bent along the diagonally diverging scored line 16 and turned toward the rear as shown in Figure 4. The two thirty degree (30°) angle diagonal cuts 19 permit the flaps 44 to be bent at ninety degree (90°) angles to the central portions 51 of the inside cover 15 without any buckling at said points.

The razor head 31 is then bent at a sixty degree (60°) angle from the vertical position as shown in Figure 5. The ends of flaps 44 provide a support for the razor head 32 when so positioned. The aluminum strip 47 is then adjusted as shown in Figure 5 to further support the razor head and is then bent at 49 to lock the razor head in operating position. When the above steps have been followed, the razor is then assembled and ready for use. The soap 41 may be removed and used to lather the face. The razor is constructed of such a material that it would be practical to dispose of the same after a single use.

From the foregoing, it will be evident that a collapsible razor constructed in accordance with this invention provides many advantages over conventional standard razor; is simple in construction, practical, inexpensive and highly efficient.

What I claim and desire to secure by Letters Patent is:

1. A disposable collapsible razor adapted to be housed in a housing similar to a paper match book cover when disassembled and capable of being extended into a regular size razor comprising: A cover of any suitable water-repellent material for housing said razor; a razor head; first means for adjustably positioning said razor head with respect to said cover; second means for extending and converting said cover into a razor handle; and locking means for maintaining said razor head in operating position, consisting of two parallel vertical slots in said cover located just below said razor head and a metal strip reinforcing the cover material bounded by said slots, said metal strip being adjustably connected to said razor head so that it may support and lock said razor head in operating position.

2. A disposable collapsible razor adapted to be housed in a housing similar to a paper match box cover when disassembled and capable of being extended into a regular size razor comprising: A cover of any suitable water-repellent material for housing said razor; a razor head; first means for adjustably positioning said razor head with respect to said cover; second means for extending and converting said cover into a razor handle; two parallel vertical slots in said cover located just below said razor head; and a metal strip reinforcing the area bounded by said slots, said metal strip being adjustably connected to said razor head so that it may support and lock said razor head in operating position.

3. A collapsible disposable razor comprising: A razor head; a housing having said razor head housed in one end thereof; means for converting the remainder of said housing into a razor handle; and second means for adjusting and locking said razor head in operating position, consisting of a transverse scored line on said housing located just below said razor head, said line enabling said razor head to partially rotate about said transverse line; two parallel vertical slots of approximately one inch in length located at the base of said razor head; a metal strip to reinforce the area enclosed by said slots, said metal strip adapted to have one end attached to said razor head so as to support and lock the same in operating position.

4. A razor comprising: A four and one-half by one and one-half (4½ x 1½) inch rectangular water-repellent paper adapted to serve as a combination housing and handle for said razor having a first and second end; two parallel transverse scored lines three-eighths (¾) of an inch apart, the lower line being located one and nine-sixteenths (1¼) inches from said first end of said rectangular paper for permitting said rectangular paper to fold and completely incase said razor; two slightly diverging scored lines extending the longitudinal length of said rectangular paper, said lines commencing one-half (½) inch from each corner of said first end, the area enclosed within said diverging lines and edges of said rectangular paper forming flaps, which are bent at a ninety degree (90°) angle to said rectangular paper to form a razor handle when in an assembled position; a third transverse scored line located fifteen-sixteenths (1½) of an inch from said second end of said rectangular paper; two thirty degree, (30°) angle cut outs on each edge of said rectangular paper commencing three-fourths (¾) of an inch from said second end of said rectangular paper on each edge of the same and terminating at said third transverse line, said cut outs preventing the buckling of said paper when said flaps are turned back; a razor head attached to and enclosed in said second end of said rectangular paper and adapted to be partially rotated about said third transverse scored line, comprised of a razor blade, a razor guard and a razor base, all of which are incased in said second end of said rectangular paper and attached thereto by means of a staple; and locking means for supporting and locking said razor head in operating position comprised of two vertical slots one and one-eighths by one-eighth inch (1⅛" x ⅛") one end of which terminates underneath said staple; and aluminum strip for reinforcing said area enclosed by said slots, said aluminum strip having one end secured under said staple, said strip being bent at said staple so as to lock and support said razor head when in operating position.
